UNITED STATES PATENT OFFICE.

SAMUEL HERBERT, OF DETROIT, MICHIGAN, ASSIGNOR TO HUTCHINS
CAR ROOFING COMPANY, OF DETROIT, MICHIGAN, A CORPORATION
OF MICHIGAN.

CAR-ROOF.

No. 845,414.

Specification of Letters Patent.

Patented Feb. 26, 1907.

Application filed May 14, 1906. Serial No. 316,802

To all whom it may concern:

Be it known that I, SAMUEL HERBERT, a citizen of the United States of America, residing at Detroit, in the county of Wayne and State of Michigan, have invented certain new and useful Improvements in Car-Roofs, of which the following is a specification, reference being had therein to the accompanying drawings.

10 The invention relates to roofs for freight-cars consisting primarily of superimposed courses of boards and an interposed waterproof fabric lining serving to prevent leakage through the board structure. In the formation of roofs of this character it is essential that the lining be not only strong and durable to withstand wear between the boards, but sufficiently pliable to yield to the strains imposed upon it occasioned by the twisting and 15 rocking movements of the car. As these types of roof have been previously constructed the linings, usually coated or saturated with a waterproofing compound, in a comparatively short period of time dry out and, before 20 coming hard and brittle, crack or break under the working strains of the car.

The object of the present invention is to produce a freight-car roof in which the lining will retain its pliability for a maximum period of time greatly in excess of the life of the ordinary roof, so that under all ordinary conditions of usage it will remain unbroken and leakage be prevented.

25 A further object is to so form the lining that if cracked by unusual strains the openings or breaks will be stopped or healed automatically and remain permanently closed.

With these objects in view the invention consists in the novel construction of the car-30 roof and in the peculiar arrangement and combination of its parts, as will be more fully hereinafter set forth.

In the drawings, Figure 1 is a sectional perspective view, showing a portion of a car-45 roof embodying my invention; and Fig. 2 is a cross-section through a portion of the lining, on enlarged scale.

The reference-letter A represents the usual roof-frame of any suitable construction, and 50 upon the roof-frame is arranged the roof proper, consisting of two superimposed courses of boards 'B B', preferably matched lumber, placed upon opposite sides of the

ridge and nailed together and to the roof-frame. Intermediate these courses is placed my improved lining, which is clamped between the boards and serves to prevent leakage through the board structure. 55

In construction the lining is composed of two external layers, preferably of wool felt J and K, either or both of which may be composed of single or multi-ply felt, as may be desired, the latter being used, preferably, to produce a more durable structure. Between these layers is arranged a central layer L, of coarsely woven or open-mesh fabric, preferably burlap. These several layers are saturated, preferably, with a waterproofing compound, as asphaltum, the central layer being supersaturated with this composition, and between the latter layer and each of the two external layers is placed a layer of the asphaltum compound indicated by the reference, letters M and O. As thus constructed the lining is provided with an excess amount of the roofing compound, which is always in a viscous or glutinous state, serving to keep the external layers in the pliable condition desired, and at the same time is enabled to enter and fill any cracks or breaks that may occur in the external layers owing to exceptional strains imposed by the car, thus healing or closing the openings and sealing the lining permanently against leakage. The interposed fabric of the lining, by reason of its coarse mesh, permits the asphaltum or any cementitious roofing compound that may be used to pass readily therethrough, so that the entire fabric is saturated. In this condition it acts as a retainer, holding the 80 glutinous compound from leakage through the external layer, while the latter serves to keep the interior of the lining air-tight. In this manner a lining is produced which, as previously stated, is always in a pliable or 85 yielding condition, giving the results described. It is also to be noticed that the lining itself, by reason of the various layers of which it is composed, is in the nature of a compound structure considerably heavier 90 and thicker than any of the linings heretofore used and having greater durability and yielding property.

The lining described is arranged upon the courses of boards, as indicated in Fig. 1, two 105 strips or sheets of the lining a and b extend-

ing longitudinally of the roof and the sheets overlapping at the ridge in the ordinary manner and being of sufficient width to extend downwardly, as indicated, to overlap 5 the interior cornices. The upper course of boards rests directly upon the lining in the usual manner and is nailed to the lower course.

What I claim is—

- 10 1. In a car-roof, the combination with the roof - frame, of superimposed courses of boards thereon, and a compound pliable waterproof lining intermediate the courses consisting of exterior layers of roofing mate-
rial saturated with a waterproof compound, a central layer of coarse open-mesh fabric supersaturated with a waterproofing compo-
sition, and a layer of cementitious water-
proofing compound in a glutinous state in-
- 15

terposed between each external layer and 20 the central layer.

2. In a car-roof, the combination with a suitable roof - frame, of two superimposed courses of boards thereon, and a compound pliable lining intermediate of and clamped 25 between said courses, consisting of exterior layers of wool felt saturated with asphaltum, a central layer of burlap supersaturated with asphaltum, and layers of asphaltum in a glu-
tinous state arranged between the exterior 30 layers and the saturated burlap.

In testimony whereof I affix my signature in presence of two witnesses.

SAMUEL HERBERT.
